Filed Oct. 6, 1969, Ser. No. 19,425

Term of patent 14 years

Int. Cl. D12—13

U.S. Cl. D14—24

FIG. 1.

FIG. 2.

FIG. 1 is a perspective view from the top, and one side of the snowmobile cowl showing our design.

FIG. 2 is a front elevation view thereof.

The rear of the raised front part of the cowl is flat and plain except for the rearward projection therefrom of a second raised portion which is visible in FIGS. 1 and 2. The rear of this second raised portion is open.

We claim:

The ornamental design for a snowmobile cowl, as shown and described.
